UNITED STATES PATENT OFFICE.

JOSEPH KOON, OF NEW YORK, N. Y., ASSIGNOR TO LEWIS SCHIELE & CO.,
OF SAME PLACE.

CORSET.

SPECIFICATION forming part of Letters Patent No. 247,662, dated September 27, 1881.

Application filed July 1, 1881. (Model.)

To all whom it may concern:

Be it known that I, JOSEPH KOON, of New York, in the county of New York and State of New York, have invented new Improvements 5 in Corsets; and I do hereby declare the following, when taken in connection with the accompanying drawings and the letters of reference marked thereon, to be a full, clear, and exact description of the same, and which said 10 drawings constitute part of this specification, and represent, in—

Figure 1, a side view of the hip-section; Fig. 2, transverse section at $x x$, enlarged.

This invention relates to an improvement in 15 corsets, with special reference to that portion which extends over the hips and upward under the arm, and commonly called the "hip-section;" and it consists in constructing the section from two thicknesses of fabric with parallel 20 pockets close to each other, starting from the upper edge and running downward to about the waist line; thence diverging from the vertical central line, those in rear of the central line curved downward and backward, those in 25 front of the said line curved downward and forward. In the space produced by the divergence of pockets other pockets are formed parallel to those each side the center, gradually shortening toward the bottom until the space 30 is filled, and into all the pockets cords or equivalent stays are introduced, as more fully hereinafter described.

A represents the front section; B, the rear section; C, the front half, and D the rear half, 35 of the hip-section. The parts C D are cut to give the required expansion at the lower edge. They are each composed of two thicknesses of fabric, $a b$, and in each of the parts parallel lines of stitches are run from top to bottom 40 parallel with each other throughout the sections to about the waist-line. From that point those in the front half, C, curve downward and forward to the lower edge. Those in the rear half curve downward and backward to the

lower edge. The curving or diverging of the 45 pockets produces a gore-shaped space at the center lower edge of the section. Throughout this gore-shaped space pockets are made in each part parallel with the respective curves until the space is completely occupied by the 50 pockets. Into these pockets, throughout the two parts of the section, cords or equivalent stays are run, thus producing a completely corded section, the cords throughout the section parallel with each other to the waist-line, 55 and from that point diverging to the front and rear.

The pockets may be first made and the cords introduced; but the better method is to introduce the cords at the time of making the 60 pockets.

If made in two parts, which is the preferable plan, the said two parts are united at the center, bringing the diverging cords in the lower portion to meet at the central seam, and at 65 that seam covered by an overlay, E.

I do not wish to be understood as broadly claiming cords or equivalent stays introduced in the hip-section, as such, I am aware, is not new; but

What I do claim is—

A corset having the hip-section corded throughout, the cords starting from the upper end of the section parallel with each other and extending down to the waist-line; thence 75 diverging from the center, those in the front half curved downward and forward, and those in the rear half curved downward and backward, the intermediate space produced by such divergence filled by other cords, those in each 80 half parallel with the other cords in the same part, and all correspondingly diverging, substantially as described.

JOS. KOON.
